VALVE SPRING SPLIT LOCK CATCHER

Filed March 16, 1932

INVENTOR:
JOSEPH SUNNEN.

BY Harry Reines
ATTORNEY.

UNITED STATES PATENT OFFICE

JOSEPH SUNNEN, OF KIRKWOOD, MISSOURI

VALVE SPRING SPLIT LOCK CATCHER

Application filed March 16, 1932. Serial No. 599,114.

My invention has relation to improvements in tools commonly used by automobile mechanics in performing certain operations on the engine thereof, and it consists in the novel 5 features of construction more fully set forth in the specification and pointed out in the claims.

The present invention relates more particularly to receptacles, or catchers, for certain 10 parts of the valve mechanism such as the split lock for holding the valve spring seat in place, and is an improvement over the device described in my Patent No. 1,764,185, dated June 17, 1930.

15 As in the device of the patent referred to, my improved receptacle, or catcher, is disposed below the valve spring around the valve stem or cam follower in position to catch the split lock when it is released on lifting the 20 valve. However, the present receptacle is more conveniently operated in that it is provided with a projecting handle and is arranged to present an opening to permit intimate association with the valve stem, said 25 opening being closed by the pressure of the receptacle against the valve stem in one direction and opened by pressure in the opposite direction without any other manipulation. In addition to ease of manipulation, it is the 30 object of the invention to provide a receptacle that is simple, durable and reliable in operation.

These advantages, as well as others inherent 35 in the invention, will be better apparent from a detailed description thereof in connection with the accompanying drawing, in which:

Figure 1 is a side elevation of a fragment of 40 an engine showing several valve stems and my improved receptacle applied to one of them; Fig. 2 is a cross-section taken on the line 2-2 of Fig. 1 with the receptacle left in elevation; Fig. 3 is a top plan of my improved 45 receptacle with the cooperating parts thereof in closed position; Fig. 4 is a top plan of the receptacle with the cooperating parts in open position to permit the reception of the valve stem; and Fig. 5 is a vertical cross-section through the receptacle taken on the 50 line 5-5 of Fig. 3.

Referring to the drawing, E represents an internal combustion engine in which the valve spring S rests on a washer or seat W held in place on the valve stem V by a split lock L. In order to remove the valve the spring must also 55 be removed by a tool known as a valve lifter. As soon as the spring is raised from its seat W by the valve lifter the pressure is released from the lock elements L which become dislodged from the valve stem V and fall. The 60 limited clearance around the valve stem, especially when the valve lifter is in place, is not sufficient for the operator to catch the lock elements in his hand, but there is sufficient space for the insertion of my improved 65 receptacle R since the receptacle accommodates itself to the space provided, as shown in Figs. 1 and 2.

The receptacle R is substantially in the shape of a circular pan and comprises sections 1 and 2 hinged together by means of a pivot 3. The section 1 is of substantially circular shape and is provided with a marginal flange 4, or a side wall, extending somewhat more than half way around its 75 periphery. The bottom 5 of section 1 has a recess 6 extending radially inwardly, the inner edge 7 of said recess being described by a radius the center of which is on the center of the receptacle R, and the opening of the 80 recess being opposite to the wall 4. The section 2 lies over the section 1 and is substantially semi-annular in shape, having a flange 8 extending around a portion of its periphery so as to form a continuation of the flange 4 when the section 2 is in its closed position 85 to cover the open end of recess 6. In this position of section 2 a substantially circular opening is formed at the center of the receptacle by the arcuate edge 7 of recess 6 and 90 arcuate edge 9 of section 2. This section 2 thus forms, what may be termed a "gate" in the receptacle, since this section may be oscillated about the pivot 3 to expose the recess 6, as shown in Fig. 4. The flange 4 is provided with an inwardly bent extremity 4' adjacent to recess 6, and flange 8 is provided with an inwardly bent extremity 8', which 95 will come into abutting relation with the flange 4' when the section, or gate, 2 is closed. 100

The flange 8 does not extend around the entire periphery of section 2, but is terminated at a point to leave a portion 10 of the bottom 11 of section 2 extending into the flanged 5 part of section 1 partially around the edge 7 of recess 6. A handle 12 is fixed to flange 4 at a point approximately on the diameter of the receptacle passing through the center of the recess 6.

10 In using my improved receptacle the operator manually rotates the section 2 with respect to section 1 so as to expose the recess 6, as shown in Fig. 4. The receptacle may 15 then be disposed around the valve stem or cam follower, as the case may be, by manipulating it so that the valve stem enters the recess 6 and finally impinges on edge 13 of section 2. As the valve stem is forced into the recess, section 2 will be moved to closed 20 position by the pressure of the valve stem against the edge 13. The operator may then lift the valve and allow the split lock elements L to fall into the receptacle, after 25 which it is withdrawn from the stem. In the withdrawing operation the action of this section 2 is reversed from its action in the entering operation, i. e., the valve stem impinges on the edge 9 of the bottom 11 and in 30 withdrawing the receptacle the gate or section 2 will be pushed open and the valve will then pass out through recess 6. It is thus apparent that after the gate 2 has once been 35 opened to permit disposition of the receptacle around the valve stem the subsequent operations of closing the gate and again opening it to permit withdrawal of the receptacle are 40 accomplished merely by the movement of the receptacle in and out in contact with the valve stem, no further manual manipulation being necessary.

Having described my invention, I claim:

1. A catcher for valve assembly parts comprising a receptacle having relatively movable sections pivotally connected, one of said sections having an open slot extending from its periphery into the bottom of the receptacle, said slot being adapted to receive one of the valve assembly parts, the other section 45 being operable as a gate to open and close said slot, and means on said gate section for engagement with the aforesaid valve assembly part whereby the gate is opened or closed by movement of the receptacle toward or 50 from said valve assembly part.

2. A catcher for valve assembly parts comprising a receptacle having relatively movable sections pivotally connected, one of said sections having an open slot extending from its periphery into the bottom of the receptacle, said slot being adapted to receive one of the valve assembly parts, the other section 55 being operable as a gate to open and close said slot, and means for closing and opening said gate section whereby said receptacle may be

applied to and removed from the valve assembly parts.

In testimony whereof I hereunto affix my signature.

JOSEPH SUNNEN.
